UNITED STATES PATENT OFFICE.

CARL HERMANN CHRISTEL, OF BERLIN, GERMANY, ASSIGNOR TO MERGENTHALER LINOTYPE COMPANY, OF NEW YORK, N. Y., A CORPORATION OF NEW YORK.

SPACER FOR USE IN TYPOGRAPHICAL MACHINES.

1,142,236.

Specification of Letters Patent.

Patented June 8, 1915.

Original application filed November 15, 1909, Serial No. 528,222. Divided and this application filed August 18, 1913. Serial No. 785,316.

To all whom it may concern:

Be it known that I, CARL HERMANN CHRISTEL, a subject of the King of Prussia and German Emperor, and resident of Belle Alliancestrasse 11, Berlin, in the Kingdom of Prussia, German Empire, have invented certain new and useful Improvements in Spacers for Use in Typographical Machines, of which the following is a specification.

10 This case is a division of my application for Letters Patent of the United States, Serial No. 528,222, filed November 15, 1909, and the invention hereinafter more particularly described consists of improved spacers 15 for use in typographical machines, in connection with matrices of the type which is provided with more than one face of the respective character, such for example, as are described in the specification of Letters Patent No. 547,633, October 8th, 1895, and No. 615,909, December 13th, 1898, the said matrices being adapted to occupy two different operative positions according to which face is to be called into requisition.

25 The "operative position" in a machine equipped with matrices is that adapted to register with the mold.

The specification of the second of the above two patents, discloses two-face matrices held with their lower faces in the operative position, by a ledge i'' (Fig. 3) while they are in and passing through the assembling elevator I, and by a ledge on a so-called blade n^{10} (Figs. 4 and 13) while they 30 are in the first elevator N. Neither of these ledges underlies the bodies of the matrices—they underlie only the coöperating bottom lugs which project to the front from the said bodies. Between the assembling elevator I and the first elevator N, there is the intermediate channel M which has a ledge at functionally the same level therein as the ledges 35 above mentioned. It is on this ledge that the front bottom lugs of the said matrices ride as they pass through the said guide M. These matrices pass through the assembler elevator I, then through the guide M, into the first elevator N and, lastly, out of it, their front bottom lugs rubbing most of the 40 time upon the said ledges. Now, as none of the said ledges underlie the bodies of the matrices, but the front bottom lugs only, all the wear on the matrices due to friction between them and the ledges, falls upon the

bottom faces of the said lugs. This wear is 55 very mischievous, because matrices so worn, will hold their lower face below the operative position, by a distance equal to that wear. The object of the present invention is to prevent or minimize such wear, by increasing the area of contact between each matrix on the one hand, and a ledge on the other, this increase being in the direction of the width of a ledge, whereby some of the body of each matrix, in addition to its front 60 bottom lug, shall rub over and rest upon the ledge.

The accompanying drawings show improved spacers according to the present invention, together with a part of a linotype 70 machine in which the said spacers are adapted to be used and matrices adapted for operative association with the said spacers. The machine here selected for illustration is the same as that chosen for the illustration of the inventions of the two patents above-mentioned, viz:—a Mergenthaler line casting machine; neither the said machine nor the matrices, however, constitute any 75 part of the present invention, they, themselves, having been embodied in an application for Letters Patent, Serial Number 528,222, filed November 15, 1909, from which the present one is a divisional application, and in a divisional application Serial Number 694,358, filed May 1, 1912.

In the said drawings:—Figure 1 is a side elevation of a matrix; Figs. 2 and 3 are vertical sections looking from the right-hand side of the machine; and Figs. 4, 5 and 6 are 80 side elevations of spacers.

1, 1 are bodies of matrices; 2, their front top lugs, and 3, their rear top lugs; 4, their front bottom lugs, and 5, their rear bottom lugs; 6, the top formative cavities, and 7 95 the bottom formative cavities for the two faces of the respective character; one of which cavities must register with the mold cavity; 8 a portion of the mold wheel; 9, the mold block fast thereon; 10, the mold cavity; and 11, the first elevator, all as heretofore.

12 is the widened ledge, the extension or extra width of which projects rearward beyond the face 13 and stands, therefore, in a position for some of the body 1 of a matrix (as distinguished from a front lug 4 of the latter) to rub over and rest upon. Matrices

that are required to have their bottom cavities 7 in register with the mold cavity 10, contact with the ledge 12 by their lugs 4 and adjacent portions of the feet of their bodies 5 1, such portions being of the same area as the extra width of the said ledge, as shown in Figs. 1 and 2. Matrices that are required to have their top cavities 6 in register with the mold cavity 10, hang in the elevator 11 10 by their lugs 2, 3 engaging on ledges 14, their lugs 4 being under the ledge 12.

As any matrix may be required to have its top cavity 6 in register with the mold cavity 10, when the extra width of the ledge 15 12 would prevent it passing into the elevator 11, by standing in the way of its body 1, each matrix has a notch 15 in its front edge, large enough to clear such extra width.

Spacers on the principle of the single or 20 of the double wedge, are well known in connection with the justification of the composed line in a typographical composing machine. To enable wedge spacers to justify the composed line, they are, if single, 25 pushed further through it; and if double, one or both of their wedges is or are pushed farther through it and over the other wedge, both pushings being effected by the movement of the justifier. But if these wedge 30 spacers should be as wide as the matrices or the type dies, their having notches 15 in their front edges, will not suffice. Such notches must, to meet the requirement of the 35 present invention, be extended lengthwise of the wedge that is to be pushed, for a distance not less than the movement of the justifier, in order that that wedge may continue to clear the extra width of the ledge 12. Thus, the spacers used in a Mergenthaler line casting machine are as wide as 40 the matrices used therein, and are also double wedge spacers. 16 and 17 are the two wedges, of different lengths, oppositely inclined, and both slidably connected together, the short wedge 16 having lugs 45 18 which engage in slots 19 in the elevator 11, to support the spacer therein and to hold the wedge 16 stationary while the longer wedge 17 is pushed through the composed 50 line and at the same time over the wedge 16 by the justifier. 20 is the extended notch. This notch may extend for nearly the whole length of the wedge, stopping short of both top and bottom, as shown in Fig. 4; or 55 throughout the joint length of both wedges, as shown in Fig. 6.

It is essential that the matrices and spacers for each line should be securely clamped together at the mold and also that 60 they should be accurately and closely pressed or clamped against the mold, in order that no metal may escape between or around the matrices when the pump is operated. The ledge 12 is made to fit the notch of each 65 matrix and to extend exactly to the bottom

of the notch when the matrix is in casting position. When thus proportioned the ledge operates as a part of the clamping devices to press the matrices firmly and uniformly against the mold. The spacers are required 70 to be not greater in width than the distance from the ledge to the plane of the face of the mold in order that they may be pushed up during the justification of the line. On the other hand the width of the spacers 75 should be equal to the width of the bodies of the matrices at the notches 15, that is, their width should be equal to the distance from the bottom of the notch 15 to the opposite side of the matrix. When thus constructed the ledge 12 will press equally upon the spacers and matrices and hold them uniformly against the mold. The ledge 12 therefore serves to sustain the matrices at the proper elevations when presenting them 80 to the mold and also to assist in pressing the matrices and spacers uniformly against the mold to prevent any escape of metal along the inner face of the matrix line.

In cases in which the matrices are 90 provided with more than two superposed formative cavities, it will be necessary to provide the said matrices with more than one notch 15 and this in a manner which is obvious to any expert. For example, matrices with 95 three superposed formative cavities will each require to have two superposed notches 15 above the lower front lug 4, and the first elevator 11 or its equivalent will require to have two superposed horizontal ledges 12. 100

Having described my invention, I declare that what I claim and desire to secure by Letters Patent, is:

1. A justifying spacer for linotype machines comprising two coöperating wedge-shaped parts, one stationary and the other movable, the movable part having a mold-engaging edge and having its opposite edge recessed, for the purpose described. 105

2. A justifying spacer for linotype machines comprising two coöperating wedge-shaped parts, one stationary and the other movable, the movable part having a mold-engaging edge and having a portion extending from the mold engaging edge to the opposite edge of less body width than that of the matrices with which the spacer is designed to be associated, for the purpose described. 110

3. A justifying spacer comprising two coöperating wedge-shaped parts, one stationary and the other movable, the said stationary part having a portion extending from the mold engaging edge to the opposite edge of less body width than that of the matrices 125 with which the spacer is designed to be associated.

4. A justifying spacer comprising two coöperating wedge-shaped parts, one stationary and the other movable, the said station- 130

ary part having a portion of less body width than the matrices at and near its lower end, and extending from the mold engaging edge to the opposite edge, for the purpose described.

5. A justifying spacer comprising two co-operating wedge-shaped parts, one stationary and the other movable, and both said parts being less in width at portions in their 10 length than the matrices with which they are designed to be associated, for the purpose described.

6. A justifying spacer comprising two co-

operating wedge-shaped parts, one stationary and the other movable, the movable part 15 having a body width at its upper end equal to that of the matrices with which the spacer is designed to be associated, and reduced in width between its opposite edges below said end, for the purpose described.

20 In testimony whereof I affix my signature in presence of two witnesses.

CARL HERMANN CHRISTEL.
